FOREIGN PATENT DOCUMENTS

GB 3001996 5/2002

Primary Examiner—Stella Reid
(74) Attorney, Agent, or Firm—Paul Y. Yee(57) CLAIM

We claim the ornamental design for a portion of a labial pad, as shown and described.

DESCRIPTION

FIG. 1 is a top plan view of a portion of a labial pad embodying our new design, with the bottom plan view being a mirror image; and,

FIG. 2 is a top plan view of a portion of a labial pad embodying our new design, with the bottom plan view being a mirror image.

The side and end elevational views are not part of the claimed design. The broken lines shown in the figures are for illustrative purposes only and form no part of the claimed design.
